UNITED STATES PATENT OFFICE

BENNETT WEINBERG, OF BUTTE, MONTANA

MATTRESS PROTECTOR

Application filed November 26, 1930. Serial No. 498,481.

The invention relates to devices for covering bed springs to protect the mattresses resting thereon, and it aims to provide an exceptionally simple and inexpensive device of this character, yet one which may be easily applied and will be of unusual advantage.

With the foregoing in view, the invention resides in the novel subject matter hereinafter described and claimed, description 10 being accomplished by reference to the accompanying drawing.

Fig. 1 is a perspective view showing the device applied to a conventional bed spring.

Fig. 2 is a top plan view of the protector, 15 partly broken away.

Fig. 3 is an enlarged longitudinal sectional view substantially on line 3-3 of Fig. 2.

Fig. 4 is an enlarged detail sectional view on line 4-4 of Fig. 2.

20 The preferred construction has been illustrated and will be specifically described, with the understanding that minor variations may be made within the scope of the invention as claimed.

25 In constructing the device, I make use of a rectangular sheet 5 of muslin or other textile material. Lying upon and preferably glued or otherwise secured to the sheet 5, is a rectangular sheet 6 of heavy paper, this 30 paper sheet being of less length and width than the sheet 5, so that the transverse and longitudinal edges 7 and 7' of said sheet 6 may be turned inwardly upon the marginal portions of said sheet 6. Two longitudinal reinforcing strips 8 of heavy paper are glued or otherwise secured upon the longitudinal edge portions of the sheet 6 and upon the in-turned longitudinal edge portions 7' of the 35 textile sheet 5, and the ends 9 of said strips 8 are shown lying upon the inturned ends 7 of said sheet 5. The bound inner edges 10 of two transverse elastic strips 11, rest upon the in-turned ends 7 of the sheet 5 and upon the 40 ends 9 of the strips 8 and stitching 12 passes

through all of the superposed parts, as shown in Fig. 3.

The outer edges of the elastic strips 11 are wrapped at 13 around two bars 14 respectively, said bars being either of wood or metal. Attaching hooks 15 to engage the ends of a bed spring 16, are provided with flat shanks 17 which rest upon the outer edge portions of the elastic strips 11, and rivets 18 pass through these shanks and the underlying portions 11, 13 and 14 of the protector. 50

In use, the protector is laid upon the spring, the hooks 15 at one end of said protector are engaged with one end of the spring, the protector is then stretched longitudinally and the hooks at its other end engaged with the adjacent end of the bed spring, and the elasticity of the strips 11 then holds the protector in smooth stretched condition and prevents release of the hooks. 60

65 By employing the details disclosed, the device may be easily and inexpensively manufactured and hence sold at small cost, but attention is again invited to the fact that minor variations may be made within the 70 scope of the invention as claimed.

I claim:

1. A mattress-protecting bed spring cover comprising a flexible inelastic sheet, two elastic strips extending along the end edges 75 of said sheet respectively and secured at their inner edges thereto, said inelastic sheet and elastic strips being substantially in the same horizontal plane, two transverse bars around which the outer edge portions of said elastic strips are rolled respectively, hooks having flat shanks lying upon said rolled edge portions of said elastic strips, and rivets 80 passing through said bars, said hook shanks and said rolled edge portions of said elastic 85 strips.

2. In a mattress-protecting bed spring cover, a lower rectangular textile sheet, an upper heavy paper sheet cemented upon said textile sheet and of less length and width 90

than the latter, the edges of said textile sheet being turned inwardly upon the upper side of said paper sheet, longitudinal reinforcing strips of heavy paper cemented upon said paper sheet and the inturned longitudinal edges of the textile sheet, transverse elastic anchoring strips having bound inner edges lying upon the inturned ends of said textile sheet, and stitching passing through said bound elastic edges, said inturned ends of said textile sheet and the ends of said paper sheet and strips.

In testimony whereof I affix my signature.

BENNETT WEINBERG.
